The ornamental design for a walkie talkie, as shown and described.

DESCRIPTION

FIG. 1 is a top, front, left side perspective view of a walkie talkie embodying our new design;
 FIG. 2 is a bottom, rear, right side perspective view thereof;
 FIG. 3 is a front elevation view thereof;
 FIG. 4 is a rear elevation view thereof;
 FIG. 5 is a left side elevation view thereof;
 FIG. 6 is a right side elevation view thereof;
 FIG. 7 is an enlarged top plan view thereof;
 FIG. 8 is an enlarged bottom plan view thereof; and,
 FIG. 9 is an enlarged view of the selected portion 9 in FIG. 1.

The broken lines shown in the drawings depict portions of the walkie talkie that form no part of the claimed design. The dot-dash broken lines represent boundaries of the enlarged portions and form no part of the claimed design.
